UNITED STATES PATENT OFFICE.

WILLIAM E. HUGHES AND JAMES B. KING, OF CLYDE, OHIO, ASSIGNEES TO THE
HUGHES GRANITE COMPANY, OF CLYDE, OHIO, A CORPORATION OF OHIO.

VENTILATING AND DRAINAGE SYSTEM.

1,339,761.

Specification of Letters Patent. Patented May 11, 1920.

Application filed November 21, 1917. Serial No. 203,264.

To all whom it may concern:

Be it known that we, WILLIAM E. HUGHES and JAMES B. KING, citizens of the United States, residents of Clyde, county 5 of Sandusky, and State of Ohio, have invented new and useful Improvements in Ventilating and Drainage Systems, of which the following is a specification, the principle of the invention being herein explained and the best mode in which we have contemplated applying that principle, so as to distinguish it from other inventions.

Our invention relates to ventilating and drainage systems for mausoleum constructions designed effectively to secure the sanitary desiccation of bodies by natural means, and particularly means forming a part thereof designed for the purpose of preventing the deposit of moisture upon the 20 mausoleum windows.

The annexed drawing and the following description set forth in detail certain means embodying our invention, the disclosed means, however, constituting but one of 25 various mechanical forms in which the principle of the invention may be employed.

In said annexed drawing:

Figure 1 represents a transverse vertical section of a mausoleum in which our improved means for ventilating and draining are provided; Fig. 2 represents a horizontal section taken in the plane indicated by the lines II—II, Fig. 1; and Fig. 3 represents a longitudinal central vertical section taken in 35 the plane indicated by the lines III—III, Fig. 1.

In said annexed drawing, side walls of our improved mausoleum construction are indicated by the ordinal 1, a rear wall by the 40 ordinal 2, and a top member by the ordinal 3. The roof 3 may be of one or more pieces, as desired, and serves as a locking device to tie the whole building together. The construction of the wall is identical with that 45 described and claimed in detail in our pending application for United States Letters Patent upon wall constructions for mausoleums, Serial No. 203,266. A lobby 4 is formed in said mausoleum adjacent to 50 superimposed inclosed receiving crypts 5, there being shown, in the exemplification of our invention illustrated in the accompanying drawing, two oppositely disposed series of such crypts. These crypts are ventilated 55 by means of wall openings 6 communicat-

ing with chambers 7 which in turn communicate by ducts (not shown) with the bottom of the several crypts 5, outlets 8 being provided in the other end of the crypts and in the upper horizontal plane thereof 60 for said air, which is discharged into an upper air chamber 19 disposed above the lobby 4 and crypts 5 and below the top member 3. Said air chamber 19 communicates with the atmosphere through the wall 65 openings 19'. There are formed ducts 10 between the side and rear walls 1 and 2 and the front wall (not shown) and the crypts 5, communication between said ducts and the atmosphere being afforded by the lower 70 wall openings 9 and the upper wall openings 11. Drainage channels 19² are provided between the chamber 19 and the ducts 10. Ventilation for the lobby 4 is afforded through the rear lower wall opening 12 75 communicating with the chamber 13 which in turn communicates by means of a duct 13' through a floor ventilator 4' with the lobby. By means of the arrangement of openings, ducts and air spaces hereinbefore described, 80 and other openings 20 hereinafter mentioned, there is created a natural draft, causing a continuous current of air to flow through the crypts, wall and lobby.

Referring particularly to the subject-matter claimed in this application, we shall now describe the following detail:

Formed in the rear wall 2 is an opening 18 communicating through openings 20 with the top of the lobby and also communicating 90 with a channel 17 which in turn at its lower end communicates by means of holes 15 with a window opening in the rear wall 2, said window opening being provided with a window 16, which window 95 opening communicates at its lower end through other openings 15 with a lower channel 14 communicating with the atmosphere by means of a lower opening 21 through the rear wall 2. 100

The above detail, in so far as applied to the ventilation and drainage of the lobby, crypts and walls, has been described and claimed in our pending application for U. S. Letters Patent upon mausoleum construction, Serial No. 203,265 together with the 105 following detail. The drainage from the crypts 5 is effected by means of ducts 22 discharging into the common duct 23 and thence through a duct 24 into the ground 110

back of the mausoleum foundation. The drainage from the lobby 4 and the elimination of condensation therein is effected through the floor ventilator 4' duct 13' to 5 the chamber 13 and thence through the duct 25 to the general drainage system 26. The chambers 7 are drained to the system 26 by the ducts 7', and the spaces 10 disposed intermediately the walls 1 and 2 and the 10 crypts 5 are drained by ducts 10'.

By the means above-described, in so far as concerns the window 16 and related elements, we very effectively assist in the whole purpose of such mausoleum constructions, 15 by preventing the gathering of moisture upon the window 16. The ventilation and drainage effected through the wall opening 21, the channels 14 and 17, the upper and lower series of holes 15 in the window frame, 20 and the upper wall outlet 18, effect this result.

What we claim is:

1. In ventilating and drainage systems, the combination of a building wall; a window opening and a window therefor provided in said wall; and channels formed in said wall and connecting the interior surface of said window with the atmosphere above and below said window.
2. In ventilating and drainage systems, the combination of a building wall; a window opening formed in said wall; and a window frame and a window therefor; a plurality of slots formed in the upper and 30 lower members of said frame and communi-

cating with the interior surface of said window; and upper and lower channels formed in said wall and communicating, respectively, at one end with the atmosphere above and below said window opening and at their 40 other ends, respectively, with said slots.

3. In ventilating and drainage systems, the combination of a building wall; a window opening formed in said wall; and a window frame and a window therefor; 45 upper and lower openings in said wall structure communicating with the atmosphere; and upper and lower channels formed in said wall structure and communicating with the interior surface of said window and with 50 said upper and lower wall openings, respectively.

4. In ventilating and drainage systems, the combination with walls and a floor forming an inclosed structure, said structure having 55 a window opening in one wall thereof, and a window frame and a window therefor; of upper and lower channels in said wall communicating with the atmosphere at their upper and lower ends, respectively, 60 and communicating at their lower and upper ends, respectively, with the interior surface of said window, upper openings in said wall communicating with said inclosed space and with said upper channel, and openings 65 in the structure floor communicating with the atmosphere.

Signed by us, this 10th day of Nov., 1917.

WILLIAM E. HUGHES.

JAMES B. KING.
